A. O. PRICE

SOUND AMPLIFIER

Filed Aug. 19, 1924

INVENTOR

ALBERT O. PRICE

BY

John O. Brady

ATTORNEY

Patented Nov. 25, 1924.

UNITED STATES PATENT OFFICE.

ALBERT O. PRICE, OF COSHOCOTON, OHIO.

DESIGN FOR A SOUND AMPLIFIER.

Application filed August 19, 1924. Serial No. 10,497. Term of patent 3½ years.

To all whom it may concern:

Be it known that I, ALBERT O. PRICE, a citizen of the United States of America, residing in the city of Coshocton, county of Coshocton, and State of Ohio, have invented a new, original, and ornamental Design for Sound Amplifiers, of which the following is a specification, reference being had to the accompanying drawing, forming part thereof.

The figure is a perspective view of the sound amplifier showing my new design.

I claim:

The ornamental design for a sound amplifier as shown.

ALBERT O. PRICE.
